UNITED STATES PATENT OFFICE.

STEPHEN J. SWANSON, OF RIVERTON, WYOMING.

EXTENSION CAR-STEP.

1,138,998.

Specification of Letters Patent. Patented May 11, 1915.

Application filed August 31, 1914. Serial No. 859,504.

To all whom it may concern:

Be it known that I, STEPHEN J. SWANSON, a citizen of the United States, residing at Riverton, in the county of Fremont, 5 State of Wyoming, have invented certain new and useful Improvements in Extension Car-Steps; and I do hereby declare the following to be a full, clear, and exact description of the invention, such as will enable others skilled in the art to which it 10 appertains to make and use the same.

This invention relates to car steps, particularly to extension steps, and has for its object the provision of one or more auxiliary steps associated with and adapted to 15 form a continuation of the ordinary steps provided upon street or railway cars and which may be folded upon the ordinary steps when not in use.

20 An important object is the provision of a device of this character which will be extremely simple and inexpensive in manufacture, efficient and durable in service, easily installed and simply operated.

25 With these and other objects and advantages in view, the invention consists in the novel construction and arrangement of parts as will be hereinafter more fully described and claimed and illustrated in the 30 accompanying drawing, in which—

Figure 1 is a front elevation of a car step having my extension step associated therewith and in its folded position. Fig. 2 is a longitudinal sectional view there- 35 through. Fig. 3 is a similar view showing the extension step swung downwardly preparatory to being secured in its extended position, and Fig. 4 is a similar view showing the extension step secured in its extend- 40 ed or operative position.

Referring more particularly to the drawing the numeral 5 designates a flight of ordinary car steps secured between sides 6.

45 My novel extension step comprises upper and lower horizontal portions 7 and 8 connected by a vertical portion 9, one extension step only being thus formed although any desired number may be made. The rear edge of the upper horizontal portion 7 is 50 provided at its ends with trunnions 10 for a purpose to be described.

Secured upon the lower end of each of the sides 6 are brackets 11 which comprise side portions 12 engaging the outer sides 55 of the sides 6 and horizontal inwardly extending portions 13 spaced from the bottom

of the lowermost step 5. The front ends of the brackets 11 are curved upwardly and are secured upon the forward edges of the sides 6, the sides 6 being curved and co- 60 operating with the upwardly extending portions 14 of the brackets to form guide ways 15.

When my device is in its inoperative position, the trunnions 10 are disposed within 65 the upper portions of the guide ways 15, the horizontal portion 7 is disposed flat upon the lower step 5, the horizontal portion 8 is disposed flat upon the second step 5 and the vertical portion 9 is disposed 70 against the riser connecting the two lowermost steps 5. A suitable handle 16 is preferably provided upon the portion 9 of the extension step to facilitate moving the step into its operative position.

75 My extension step being in its folded position, as shown in Figs. 1 and 2, in order to extend it for use, it is merely necessary to grasp the handle 16 and swing the extension step outwardly and downwardly into 80 the position shown in Fig. 3, the trunnions 10 being then disposed within the lower ends of the guide ways 15. The extension step is then shoved rearwardly so that the trunnions 10 and the horizontal portions 11 85 will be disposed between the retaining portions 13 of the brackets 11, and the bottom of the lowermost step 5. The extension step will then be held securely in place ready for 90 use.

In order to retain the step in its folded position, it is merely necessary to grasp the extension step and pull it forward from under the step 5 until the trunnions 10 are disposed in the guide way 15. The step is 95 then moved upwardly until the trunnions are disposed within the upper portions of the guide ways 15, after which it is merely necessary to fold the step upwardly, whereupon it will be disposed upon the step 5 as 100 previously described.

From the foregoing description and a study of the drawing it will be apparent that I have thus provided a simple and novel auxiliary step for railway trains, 105 street cars and the like, which may be readily extended for use and held rigidly in place while in such position, and which may be quickly folded upon the regular steps and be out of the way.

110 It will be readily understood that I reserve the right to make various changes in

the form, construction and arrangement of parts without departing from the spirit of the invention or limiting the scope of the subjoined claim.

5 Having thus described my invention, I claim:

The combination with a flight of car steps, of an extension step comprising horizontal portions connected by a vertical portion, trunnions at the ends of the rear edge 10 of the uppermost horizontal portion, and brackets secured upon the flight of steps and spaced from the lower end of the front

portion of the sides of the flight of steps forming guide ways journaly receiving 15 said trunnions, and said brackets having inwardly extending flanges spaced below the bottom of the lowermost one of the flight of steps and slidably receiving said trunnions.

In testimony whereof, I affix my signature, in the presence of two witnesses.

STEPHEN J. SWANSON.

Witnesses:

M. J. MARTIN,
W. F. BRENIMAN.
